MECHANICAL TOY VEHICLE

Carl Arnold, Nuremberg, Germany

Application June 3, 1939, Serial No. 277,247
In Germany November 28, 1938

6 Claims. (CL 46—201)

This invention relates to a mechanical toy vehicle in the form of a motor car or the like. The invention consists in that, within a toy motor car without spring motor but provided with runner wheels, a second small toy motor car with spring motor is inserted which, after a predetermined time, is propelled out of the larger motor car through the intermediary of a rotating cam disc, a two-armed lever and by spring pressure, and then tows the larger motor car. A toy motor car constructed in this manner affords great amusement to children.

An embodiment of the invention is illustrated by way of example in the accompanying drawing, in which—

Fig. 1 shows in side elevation the two toy motor cars telescoped one within the other.

Fig. 2 shows in side elevation the two motor cars in extended position.

Fig. 3 shows partly in elevation and partly in longitudinal section the telescoped motor cars with their body work removed.

Fig. 4 is a top plan view of Fig. 3.

Fig. 5 shows in top plan view the hitch plate for the larger car.

A body work 3 is fitted on a chassis 1 equipped with runner wheels and has two upright frames 2 one on each side. The chassis 1 has a partly open space 4 between the frames 2. A box 6 with aperture 5 is fixed on the underside of the chassis 1, whereas a plate 8 acted upon by spring 7 is slidable on the chassis 1 and has a striker 11 having an aperture 10, said striker being bent downwards at an angle and projecting through an aperture 9 in the chassis 1. This striker 11 is adapted to strike under the action of the springs 7 against an anvil 12 fitted on the chassis 1.

The plate 8 and the striker 11 are held down by the rear wheel axle 13. A second motor car 14 with spring motor 15 is placed in the free space 4 in the chassis 1 of the motor car 3 (Figs. 3 and 4). The radiator bonnet 16 of the car 3 can be folded up on a hinge to allow the introduction of the car 14. The chassis 17 of the car 14 has a nose 18 which engages in the aperture 5 of the box 6 fitted on the chassis 1 of the car 3 and thus interlocks the cars 3 and 14. The winding pin 19 of the spring motor 15 carries an eccentric disc 21 having an outwardly bent nose 20. This nose 20 alternately lifts and releases a two-armed lever 22, 23 oscillatable on the spring motor 15. This two-armed lever 22, 23 cooperates with the nose 20 of disc 21 to release the car 14 from the car 3. The car 14 has at its

rear end a strap 24 in which a hitch plate 25 (Fig. 5) is inserted. This plate 25 has notches 26 one on each side which engage in incisions 27 of the bent up frame 2 of the chassis 1 of the larger car 3 when the small car 14 has been pushed out of the car 3, with the result that the two cars are coupled. Consequently, the smaller car hauls the larger car which has no spring motor. On the chassis 17 of the car 14 a bumper bar 28 is fitted which engages in downwardly bent flaps 29 on the chassis 1. This arrangement serves to ensure the correct introduction of the small car in the larger car.

The operation is as follows:

In position of rest the small car 14 is within the larger car 3, the nose 18 of the car 14 being engaged in the aperture 5 of the box 6 of car 3. The striker plate 11 acted upon by the springs 7 is then pulled forward and its aperture 10 slipped over the nose 18 of car 14. A percussion cap is then placed on the anvil 12. When this has been done, the spring motor 15 of car 14 is wound. Both cars are then placed on the ground and are propelled by the spring motor. As the cam disc 20, 21 rotates, the front arm 22 of lever 22, 23 is raised and its rear arm 23 lowered. As the disc continues to rotate and presses against the chassis 1 with the result that firstly the cap firing device is released and secondly the driven wheels 30 of car 14 are raised from the ground. Both cars 3 and 14 now come to a standstill and the spring motor continues to run. The cam disc 21 continues to rotate and presses the arm 23 further down until the nose 18 disengages from the aperture 5 in box 6 and releases the motor car 14 from the car 3. A blade spring 31 or any other suitable device fitted on the body of the car 3 and tensioned during the insertion of car 14 precipitates forward the car 14 which in pressing the radiator bonnet outwards leaves the larger car 3. The hitch plate 25 connected to car 14 participates in the forward movement until the notches 26 engage in the incisions in the upright frames 2. The larger car is then hauled by the small car until the motor has run down.

If the bonnet 16 is again raised, the car 14 can be returned into the car 3. The nose 18 engages the aperture 5 of box 6 thereby locking the car 14 in the car 3. The spring is at the same time pressed backwards and brought into tensioned position.

If it is not desired to haul the car 3, it is only necessary to disengage the hitch plate 25 from strap 24 of the small car 14. The connection between the two cars is then lacking. The larger

car 3 without motor remains standing, whereas the smaller car 14 continues to run until its motor has run down. However both cars can be run together without being separated. For this purpose a latch 32 is pivoted on the hitch plate 25 and raises and locks the lever arm 23. Consequently, the other arm 22 of the lever is out of the range of the nose disc 21.

Other toy vehicles such as a toy motor bus and 10 tractor, may be used instead of toy motor cars.

I claim:

1. A mechanical toy comprising in combination a motorless toy vehicle, a second vehicle smaller than and adapted to be accommodated in said 15 motorless vehicle, means for locking said small vehicle in said motorless vehicle, a motor in said smaller vehicle for propelling the same, a cam disc driven by said motor, a two-armed lever acted upon by said disc to disengage said locking means, means in said motorless vehicle for expelling said smaller vehicle, and means for automatically connecting said motorless vehicle to said smaller vehicle at the expulsion of the latter.

2. In a mechanical toy as in claim 1, a chassis of the smaller vehicle, a nose on said chassis, a box on the motorless vehicle having an aperture adapted to receive said nose to lock said smaller vehicle in said motorless vehicle and 20 acted upon by the two-armed lever to release said nose.

3. In a mechanical toy as specified in claim 1, a chassis of the motorless vehicle, a chassis of the smaller vehicle, runner wheels on said last 25 mentioned chassis driven by said motor and adapted to propel the vehicles fitted one in the other, a nose on said chassis, a box on the chassis of said motorless vehicle having an aperture adapted to receive said nose to lock said smaller

vehicle in said motorless vehicle, and acted upon by the two-armed lever, said lever adapted under the action of the cam disc first to bear against the chassis of said motorless vehicle to lift said runner wheels off the ground and bring said vehicles to a standstill and then to press said box out of engagement with said nose to release said smaller vehicle.

4. A mechanical toy as specified in claim 1, in which the connecting means between the two vehicles comprises a strap on the smaller vehicle, a hitch plate removably inserted in said strap and having notches one on each side, upright side chassis frames on the motorless vehicles each having an incision adapted to automatically engage with one of said notches at the 15 expulsion of said smaller vehicle to connect the two vehicles.

5. In a mechanical toy as specified in claim 1, a bonnet hingedly mounted on the motorless vehicle adapted to swing upwards at the expulsion of the smaller vehicle to allow the passage of said smaller vehicle from said motorless vehicle.

6. A mechanical toy as specified in claim 1, in which the connecting means between the two vehicles comprises a strap on the smaller vehicle, a hitch plate removably inserted in said strap and having notches one on each side, upright side chassis frames on the motorless vehicles each having an incision adapted to automatically engage with one of said notches at the 25 expulsion of said smaller vehicle to connect the two vehicles, and a catch oscillatable on said hitch plate and adapted during the insertion of said smaller vehicle into said motorless vehicle 30 to press the two-armed lever out of the range of the cam disc to prevent the disengagement of the locking means.

CARL ARNOLD.
